VAPOR SUPPLYING DEVICE FOR MOTORS

Edward L. Bloomberg, Cleveland Heights, Ohio

Application March 16, 1931, Serial No. 523,135

6 Claims. (Cl. 123—196)

This invention, as indicated, relates to a vapor supplying device for motors. More particularly it comprises a vapor supplying device adapted to supply at a substantially constant rate to the combustion chambers of a gasoline engine a vapor, preferably formed of oil capable of withstanding high temperature, with a view, among other things, of eliminating sticky valves, preventing the formation of carbon, promoting quiet running of the motor, and retaining the cylinder compression.

Heretofore it has been proposed to supply oil or water vapor to combustion chambers of gasoline engines through the intake manifold directly or through the carburetor and manifold, with a view to improving the running conditions of the motor and preventing the formation of carbon, but such devices have not been provided with automatic means for making substantially uniform the quantity of vapor so supplied whether the motor was idling or operating at high speed.

The principal object of the present invention is to provide an improved device for supplying vapor of the character indicated to the combustion chambers of a gasoline engine to improve the operative conditions thereof. Another object of the invention is to provide a pressure responsive control for the vapor supply to the combustion chambers, which will be proportioned so as to supply vapor in accordance with the needs of the engine at various rates of speed. Another object of the invention is to provide a device of simple construction and easily adjusted to various operating conditions, which will supply suitable vapor to the combustion chambers of a gasoline engine in predetermined amounts for various rates of speed. Other and further objects of the invention will appear in the course of the following description.

Figure 1 is a view in elevation and partly in section showing a vapor supplying device for a gasoline engine embodying the principles of the invention;

Figure 2 is a fragmentary view of a modified form of device similar to that shown in Figure 1;

Figure 3 is a view showing a further modified form of device in which a different type of fluid outlet is employed; and

Figure 4 is a modified form of construction of the general type shown in Figure 3.

As is shown in Figure 1 of the drawings, the preferred form of vapor supplying device 1 is preferably supported by means of a bracket 2 secured to the front of the instrument panel 10 of an automobile. The bracket preferably is formed integrally with the top or cover section 3 of the device which is held in air-tight relation with the base section 4 which serves as a container for the liquid used in forming the vapor. The base section is preferably in the form of a glass

jar open at its upper end and held against the top or cover section by means of a stirrup or U-shaped clamping member 5 engaged through suitable ears (not shown) at the sides of the cover section, the ends of the member being screw-threaded to be engaged by thumb nuts 6.

The cap is preferably provided on its upper side with upstanding bosses 7, 8, and enlargements 11, 12 on its under surface beneath said bosses, respectively. It is also provided with a thickened wall section 13 adjacent one corner, through which a screw-threaded aperture is provided to receive an adjusting screw 14 formed with a knurled head 15 and a lower section or shank 16 of reduced diameter, at the extreme end of which is engaged a disc 17 forming an abutment for a coiled spring 18 engaged about the reduced shank of said adjusting screw, above which spring is provided a bearing member in the form of a ball 19 centrally perforated to engage about the reduced shank of the adjusting screw. At the point where the main body portion of the adjusting screw meets the reduced shank thereof, the surface is preferably rounded to provide a fixed bearing member 21 for a purpose presently to be described. A lock nut 22 may be engaged on the screw-threaded body section of the adjusting screw in a position to engage against an inclined surface 23 on the cap member to prevent vibration changing any set adjustment of the screw.

The boss 7 on the upper surface of the cap or cover member is provided with a central recess and is of extended height providing a sight feed in the form of a lateral aperture 24 through which may be seen a section of a glass cylinder 25 held between packing elements 26, 27, under pressure of a coupling member 28 which may be locked in place by a special lock nut 29. The vapor supply line 31 is connected by a suitable terminal element 32 with the coupling member 28 and by another coupling element 33 with the intake manifold 34 of a gas engine.

Centrally of the recess in the boss 7 a small aperture is provided, on the under side of which is formed a conical seat 35 for engagement with the conical point of a needle valve 36. The boss 11 on the under side of the cover is provided with a recess 37 in alignment with the recess 38 in the boss 7 and a screw-threaded sleeve 39 engaged therewith provides a support for the shank 41 of the needle valve. The space intermediate the screw-threaded sleeve and the needle valve provides a reservoir for the vapor preliminary to its entering the vapor supply line to the intake manifold. The sleeve 39 is provided with a countersunk recess 42 on its under surface adapted to receive a spring 43 engaged about the shank of the needle valve and bearing against a fixed abutment 44 thereon adjacent its lower end. The spacing of the abutment from the under face of

the sleeve 39 is such as to prevent complete seating of the needle valve at any time. The recess in the enlargement 11 is provided with a lateral passageway 45 communicating with the reservoir, 5 and said passageway opens into the container above the level of the liquid therein. A filler plug 46 provided with a tubular extension 47 which is of a length to closely approach the bottom of the container, is provided intermediate the bosses 10 1 and 8 to admit the outside air to the container closely adjacent the bottom so that air entering through a central air vent 48 in said plug may be discharged through the open end of said extension, and agitate said liquid to produce an oil-carrying vapor in the upper portion of the chamber above the liquid level.

The boss 12 is provided with an enlarged recess 49 screw-threaded to receive a cup-shaped casing 50 having an air vent 51 within which is positioned a metal bellows 52 sealed at its marginal portions against the upper edge of the casing and held in air-tight relation thereto by means of a screw-threaded cap member 53. The cap member is preferably provided with an upstanding boss 54 having a central passageway 55 which communicates with a vacuum line 56 connected with the intake manifold of the gasoline engine. The upper end of the bellows is formed with a central inlet 58 in alignment with the passageway 30 55. A nipple 57 is engaged about the screw-threaded portion of the upstanding boss to secure such line to the cap member, and a suitable nipple 60 is provided to connect said vacuum line with the intake manifold. The lower surface of the bellows is provided with a downwardly extending rod 61 which passes through the aperture 62 in the base of the casing and an aperture 63 in the boss 12 in alignment therewith. The lower end of said rod is screw-threaded to receive a nut 64 and a lock nut 65 providing an abutment for the coiled spring 66 engaged over said rod and bearing against the under surface of the enlargement 12 about said aperture. The lower end of the rod is provided with a transverse aperture 45 through which a pivot pin 67 is engaged, said pivot pin forming a support for a control lever 68 extending substantially horizontally across the container adjacent its upper portion. The control lever is preferably provided with a slot 70 50 adjacent its free end which permits the same to be engaged about the reduced shank on the adjusting screw intermediate the fixed bearing surface thereon and the spring pressed ball bearing heretofore described. The lever is formed with a slightly rounded bearing surface adjacent the point of its connection with the adjusting screw 55 against which the lower end of the needle valve bears.

The device just described is adapted to maintain a substantially uniform vapor supply to the combustion chambers through the action of the metal bellows control mechanism. Thus, as the effective vacuum in the intake manifold of the engine grows less with the wider opening of the 60 throttle and higher speed, the bellows will expand, shifting the end of the control lever down and lowering the needle valve and allowing more lubricating vapor or the like to be taken into the engine. As the vacuum becomes more effective 65 again through the closing of the throttle, reverse action to that described will take place and instead of feeding more vapor, the needle valve will close to reduce the amount being fed.

In place of using a bellows of the type illustrated in Figure 1, wherein the suction of the

engine acts through the passageway 56 to reduce the air pressure within the bellows and permits the atmospheric pressure on the outside thereof to collapse the same when the low speed operation of the engine is in effect, a closed bellows 5 of the type shown in Figure 2 may be used, in which event the pivot point for the control lever is also moved to a new position.

In said modified form of construction shown in Figure 2, the casing 71 has no air vent and the vacuum line 56 connects with the interior of the casing and reduces the air pressure about the bellows 72. The bellows is of the completely closed type, having a predetermined amount of air or gas within the same and is suitably supported by means of a spider 73 engaged between the cap member 53 and the cup shaped casing 71. The lower surface of the bellows is provided with a downwardly extending rod 74 which closely fits the passageway 75 through the boss at the 20 lower end of the casing and extends through an opening 76 in alignment therewith. The lower end of the rod is provided with a coil spring and its abutment and a lock nut therefor, as well as a pivot pin for the control lever similar to that 25 shown in Figure 1. The control lever 77 is provided with an intermediate aperture 78 through which the reduced shank portion 79 of the adjusting screw 81 is engaged.

The adjusting screw, in place of being positioned within the top section of the container at one corner thereof, is set through the top wall 82 of the casing and extends vertically downward therefrom. A lock nut 83 permits the adjusting screw to be held at any predetermined position. 30 The free end of the control lever 84 abuts against the lower end of the needle valve which functions in exactly the same manner as the needle valve shown in Figure 1. It is unnecessary to describe in detail the remaining elements of the structure, 40 inasmuch as they correspond almost exactly in every respect to those shown in Figure 1.

The modified form of construction shown in Figure 3 of the drawings discloses an apparatus for delivering a small stream of oil or other liquid 45 designed to prevent carbon formation, to the intake passageway of a gas engine. The parts of the apparatus in most of the instances shown are identical with those shown in Figure 1 and like reference characters have been applied thereto. 50 The features of the construction differing from the devices heretofore described will now be set forth.

The container 1 is supported upon a bracket 91 secured to the front of the instrument panel 92 of an automobile. The bracket preferably has on its upper side a plurality of spring fingers 93, 94, within which the base section 4 for the liquid used is held. The container may be firmly held within the clips by means of a band 95 preferably 55 of spring material engaging about the spring fingers. The container is preferably in the form of a glass jar open at its upper end and having set thereover a cap or cover member which serves as a closure for the container and as a support for the various elements of the device.

The cap member is preferably secured to the upper portion of the container in air-tight relation by means of cement or any other suitable sealing means (not shown).

The needle valve, control lever, and bellows and associated parts are all disposed as shown in Figure 1, but in place of admitting air through the filler plug and its extension, to agitate and vaporize the liquid within the container, the device 70 75

has a filler plug 96 with an air vent but without an extension. The lateral passageway to the reservoir and the line to the intake manifold is provided with a tubular extension 97 through which 5 liquid is drawn and carried toward the point of discharge into the intake manifold where it meets the ascending fuel mixture and mingles therewith.

The modified construction shown in Figure 4 10 incorporates the construction shown in Figure 2 and heretofore described in detail, but in place of admitting air to the filler plug and its extension to agitate and vaporize the liquid within the container, the device has a filler plug with an air 15 vent, but without an extension therefrom to the lower portion of the liquid. The lateral passageway to the reservoir and the line to the intake manifold is provided with a tubular extension through which liquid is drawn and carried toward 20 the point of discharge into the intake manifold where it meets the ascending fuel and mixture and mingles therewith. This construction differs from that shown in Figure 3 merely in that it uses the closed type of bellows and has a different 25 position of the fulcrum for the control lever in which latter respects it, as heretofore stated, resembles the construction shown in Figure 2.

Other modes of applying the principle of my 30 invention may be employed instead of the one explained, change being made as regards the structure herein disclosed, provided the means

Other modes of applying the principle of my 35 equivalent of such stated means be employed.

I therefore particularly point out and distinctly 40 claim as my invention:

1. An apparatus of the character set forth, having in combination a container comprising a liquid receptacle and a closure therefor provided with an air vent, a fluid delivery passageway communicating with said container and operatively 45 connected therewith at all times through a minimum opening with the intake passageway of a gasoline engine, and means wholly independent of said first-named passageway responsive to speed variations in said engine associated with the intake passageway of said engine for increasing said opening for the admission of fluid to said first-named passageway, said means being wholly 50 separate from said fluid delivery passageway.

55 2. An apparatus of the character set forth, having in combination a container comprising a liquid receptacle and a closure therefor provided with an air vent, a fluid delivery passageway communicating with said container and operatively connected therewith at all times through a minimum opening with the intake passageway of a gasoline engine, and pressure responsive means wholly independent of said first-named passageway associated with the intake 60 passageway of a gasoline engine and operable proportionally to the speed of said engine for increasing said opening for admitting a greater amount of fluid to said first-named passageway at high speed than at idling speed of said engine, said means being wholly separate from said fluid delivery passageway.

65 3. An apparatus of the character set forth, having in combination a container comprising a liquid receptacle and a closure therefor provided with an air vent member extending downwardly and opening adjacent the bottom of said liquid receptacle, a fluid delivery passageway communicating with the vapor space above the

liquid level in the upper part of said container and connected with the intake passageway of a gasoline engine, a valve associated with said passageway for controlling the amount of fluid admitted thereto, means to prevent complete seating of said valve at any time, and pressure responsive means wholly independent of said first-named passageway connected with said intake passageway for controlling the degree of opening of said valve, said means being wholly separate 10 from said fluid delivery passageway.

4. An apparatus of the character set forth, having in combination a container comprising a liquid receptacle and a closure therefor, an air inlet passageway extending into the liquid within 15 said container and adapted to agitate and partially vaporize said liquid, a fluid delivery passageway communicating at one end with the space above the liquid level in said container and at the other end with the intake passageway 20 of a gasoline engine, a valve associated with said passageway for controlling the amount of vapor formed in the space above said liquid level admitted thereto, means to prevent complete seating of said valve at any time, and pressure 25 responsive means wholly independent of said first-named passageway connected with said intake passageway for controlling said valve, said means being wholly separate from said fluid 30 delivery passageway.

5. An apparatus of the character described, having in combination a container adapted to receive a fluid suitable for the prevention of carbon formation in gasoline motors, a cover for said fluid container having an air vent and providing 35 an outlet fluid delivery passageway from the interior of said container, means connecting said passageway with the intake passageway of a gasoline engine, a valve associated with said outlet passageway of said container, means to prevent 40 complete seating of said valve at any time, a control lever associated with said container and operatively related to said valve, adjustable means for pivotally supporting said control lever, and pressure responsive means associated with 45 said control lever for controlling the position of said valve, said pressure responsive means having means wholly independent of said first-named passageway connecting the same with the inlet passageway of said gasoline engine. 50

6. An apparatus of the character described, having in combination a container adapted to receive a fluid suitable for the prevention of carbon formation in gasoline motors, a cover for said fluid container having an air vent and providing 55 an outlet fluid delivery passageway from the interior of said container, means connecting said passageway with the intake passageway of a gasoline engine, a valve associated with said outlet passageway of said container, a control lever 60 associated with said container and operatively related to said valve, adjustable means for pivotally supporting said control lever, and pressure responsive means associated with said control lever for controlling the position of said valve, 65 said pressure responsive means comprising a sealed bellows having a predetermined internal fluid pressure and an independent passageway to the intake manifold for providing under operative conditions reduced pressure exteriorly of 70 said bellows, said means being wholly separate from said fluid delivery passageway.

EDWARD L. BLOOMBERG.
